UNITED STATES PATENT OFFICE.

MARTIN P. BOSS, OF OAKLAND, CALIFORNIA.

APPARATUS FOR AMALGAMATING ORES.

SPECIFICATION forming part of Reissued Letters Patent No. 10,549, dated January 13, 1885.

Original No. 248,568, dated October 25, 1881. Application for reissue filed August 14, 1883.

To all whom it may concern:

Be it known that I, MARTIN P. BOSS, of 5
Oakland, Alameda county, State of California, have invented an Improved Apparatus
for Amalgamating Ores; and I do hereby
declare that the following is a full, clear, and
exact description thereof, reference being had
to the accompanying drawings.

The main idea embodied in my invention is
10 the amalgamation of the precious metals con-
tained in ore pulp by maintaining a circula-
tion of mercury and pulp at one and the same
time in such a manner that the mercury is fil-
tered or leached through the pulp and drawn
15 off through one source, while the pulp passes,
by means of other channels, through other
tanks for similar or different treatment.

Having devised appropriate apparatus for
20 accomplishing this object, I find that said ap-
paratus can be used in a more extended way
for treating the pulp. In fact, the arrange-
ment is such that one or more processes can
25 be carried on at the same time, and the circula-
tion extended or restricted to a greater or
less number of pans, thus giving the operator
complete control over the pulp, all as herein-
after more fully described.

Referring to the accompanying drawings,
30 Figure 1 represents a perspective view of my
apparatus. Fig. 2 is a top view of the pans
and troughs. Fig. 3 is a detail view of the
pans and quicksilver-cups.

The apparatus I arrange on benches in the
usual way. On the upper bench I mount two
35 or more hoppers, A A', which are connected
together so that the pulp which is admitted to
one will overflow into the other. The pulp is
introduced into the hopper A through a trough,
B, and when this hopper is filled to the height
40 of the dividing-partition it overflows into the
hopper A'. This latter hopper has also an
overflow through the holes a a in its side,
which are at about the same height as the top
45 of the dividing-partition. The discharge or
outlet through the lower end of each hopper
is regulated by a cone-shaped plug formed on
the end of a screw-rod, C, which passes
E, at its top, so that by elevating the plug the

size of the hole is increased. A trough, F, 50
passes along below the discharge-passages of
the hoppers, and extends out to one side, where
two inclined spouts, G G', lead from it. A
conveyer-screw, H, is placed in this trough,
and is rotated by power applied to a pulley on 55
its end, so that the pulp is fed along by the
screw.

On the next bench below a number of pans,
I I I, are placed side by side, the two adjoin-
ing pans at the right-hand end of the series 60
being placed so as to receive the pulp from the
spouts G G'. These pans are all placed close
together, and communication is established
from one to another by means of openings j
near their upper edges, so that they will over- 65
flow into each other. An inclined trough,
K, extends along outside the entire series
near the top of the pans, and each pan has an
opening, l, leading from it into the trough at
about the same level as the openings j. The 70
two adjoining pans at the left-hand end of
the series have each an overflow-opening and
spout, m, which discharges the pulp into a
lower series of pans, hereinafter described.
It will now be noticed that each pan has two 75
overflow-openings—one connecting it with the
adjoining pan and the other with the trough
K, which connects the entire series—so that by
plugging up the openings in either pan it is
cut out of the circulation without interfering 80
with the operation of the remaining pans. The
object of having two receiving and two dis-
charge pans at each end of the series is to en-
able the feed to be shifted into one or the other,
as desired, in case one should become clogged 85
or require repairs. A gate (not shown) will
therefore be placed across the trough K it is
desired to close.

On the next lower bench one or more larger
pans, O O O, are placed. These pans are con- 90
nected so as to overflow into each other in the
same manner that the upper series of pans are
connected, and a trough, P, connects their
side overflows in the same way.

Each pan I has a discharge-tube, q, Fig. 3, 95
connecting with its bottom, which leads into
a spout, R, and the spouts of each two adjoin-
ing pans I empty into the same pan O, as

shown. A quicksilver-cup, *s*, is placed on each discharge-tube *q*, into which the quicksilver will rise with the level of that in the pan through the orifice *q'* when the end of the 5 tube is plugged. Inside of each cup is a short tube, *t*, Figs. 2 and 3, the lower end of which connects with a main tube, *V*, which extends along under the entire number of cups. The upper end of the tube *t* does not extend to the 10 top of the cup, so that the quicksilver will overflow into the upper end of the tube and be conducted into the main pipe *V*. This main pipe *V* will connect with a quicksilver-pump, by which the quicksilver will be raised 15 and introduced into either or all of the pans, as desired, so as to produce a continuous circulation of the quicksilver. I have not deemed it necessary to illustrate this pump. Any one capable of performing the operation can be 20 used, the object being merely to take the quicksilver from a low level and restore it to a higher level. Any mechanism capable of effecting this object can be used with satisfactory results.

25 The process will then be as follows: The pulp being first introduced into the hopper *A*, the heavier part settles and the lighter part overflows into the hopper *A'*, the lighter part of the latter portion running off through the 30 holes *a a*. The cone-plug being properly regulated, the pulp falls into the trough *F*, and is conveyed by the screw *H* to the spout *G*, down which it passes into the pan *I*. It then overflows from pan to pan until all are filled, the 35 current being strong enough to prevent it from settling. In one or more of these pans I supply a constant stream of mercury, which filters through the pulp, amalgamating the metals, and passing down rises in the quicksilver-40 cup until it overflows into the circulating-pipe; thence it is drawn by a pump in the usual way and introduced into the pan or pans again, thus giving a continuous circulation of mercury through the pulp and keeping 45 the mercury in good condition. By this means I amalgamate the particles so that they will either be saved in the amalgam or caught in the concentrator, through which the pulp is finally passed.

50 The quicksilver used in the process will sink on all occasions, by reason of its great relative weight, and will find its way into the pipe *V* ultimately, where it is submitted to the action of the pump, or is otherwise elevated and restored to the pans containing the 55 pulp.

If desired, one or more of the pans can be cut out of the circuit after they are filled by plugging the passages, as above described, 60 and the pulp contained in them treated chemically; or chemicals can be introduced into some of the pans and mercury in others, as the operator desires. After passing into the lower settlers or large pans, *O*, where the heavier 65 particles are settled, the pulp is conducted by a spout, *W*, from the terminal pan upon a

concentrator, which will form the subject-matter of a separate application for patent. The central posts or axes in the pans are to support the mullers.

70 The pans *I* and settlers *O* are all of them the kinds of pans that are in ordinary use. Each series of pans and settlers stands upon nearly or quite the same level, and each runs full or nearly full of pulp, so as to furnish time and opportunity for the precious metals 75 to amalgamate with the quicksilver and separate from the worthless mass of the pulp. By this apparatus the pulp is constantly fed into the first one or two pans, and is constantly 80 passing through the series of pans and settlers, being reduced as it goes along, and the waste mass of the pulp is constantly discharged from the last large pan or settler *O*. This continuous movement of the pulp while 85 being reduced in pans and settlers, or settling-pans, has never before been successfully accomplished.

I am aware that it has been heretofore proposed to connect a series of vessels in such 90 manner as to discharge into each other by overflow, and also to arrange a number of amalgamating-pans at different levels, and discharging by bottom outlets into each other. I am not aware, however, that it has ever 95 been proposed, prior to my invention, to arrange two different series of vessels, one discharging the functions of an amalgamator, and connected together by overflow-pipes in such manner as to maintain a constant equal 100 circulation of the pulp therein, and the other connected in like manner and of greater size, so as to retard the current and permit a settling impossible to secure if the vessels were of the same size as those of the first series.

105 Having thus described my invention, what I claim, and desire to secure by Letters Patent, is—

1. The combination, with the hoppers *A* *A'*, and the trough *F*, having the feeding-screw *H*, and the right-angled arranged spouts *G G'*, of the series of pans *I*, connected together by pipes *j*, and having a common trough, *K*, connected thereto by pipes *l*, substantially as and for the purpose set forth.

110 2. The pan *I*, having the discharge-pipe *q*, provided with an orifice, *q'*, in combination with the cup *s*, having an overflow-tube, *t*, reaching down through its bottom and emptying into the trough or pipe *V*, substantially 120 as and for the purpose set forth.

3. An apparatus for treating ore-pulp, consisting of the hoppers *A* *A'*, trough *F*, with its conveyer-screw *H*, and spouts *G G'*, the connecting series of pans *I*, with their overflows *j l*, and trough *K*, and having the discharge-tubes *q*, the quicksilver-cups *s*, with the overflow-pipes *t*, and the main pipe *V*, and the lower set of settling-pans, *O*, connected by overflows, as described, all combined and 130 arranged to operate substantially as above specified.

4. The combination of the series of pans I, connected together by overflow-pipes *j*, and the settling or separating series of larger pans O, also connected together by overflow-pipes, with a discharging-viaduct connecting the terminal pans of the first series with the primary pan of the second series, whereby a continuous circulation of the pulp from pan

to pan is secured until it is thoroughly reduced, and finally discharged from the last 10 large pan or settler as waste tailings, substantially as shown and described.
